CLAIM

The ornamental design for a grilling bag, as shown and
described.

DESCRIPTION

FIG. 1 is a top right front perspective view of a grilling bag
in the closed configuration showing my new design;

FIG. 2 is a top plan view thereof;

FIG. 3 is a bottom plan view thereof;

FIG. 4 is a front elevational view thereof;

FIG. 5 is a right side elevational view thereof, the left side
elevational view being a mirror image;

FIG. 6 is a rear elevational view thereof;

FIG. 7 is an enlarged sectional view thereof taken along line
7-7 in FIG. 2;

FIG. 8 is a top right front perspective view of a grilling bag
in the open configuration showing my new design;

FIG. 9 is a top plan view thereof;

FIG. 10 is a bottom plan view thereof;

FIG. 11 is a front elevational view thereof;

FIG. 12 is a right side elevational view thereof, the left side
elevational view being a mirror image; and,

FIG. 13 is a rear elevational view thereof.

The broken lines in each of FIGS. 1 to 13 showing fasteners
for securing the grilling bag in the closed configuration from
no part of the claimed design. The break lines and brackets
in each of FIGS. 1 to 13 indicate indeterminate length and
width of the grilling bag, and the appearance of any portion
of the grilling bag between the break lines forms no part of
the claimed design.
